CLAIM

An ornamental design for an “animal toy,” as shown and described.

DESCRIPTION

FIG. 1 is a front perspective view of the animal toy;

FIG. 2 is a front view of the animal toy;

FIG. 3 is a rear view of the animal toy;

FIG. 4 is a right view of the animal toy;

FIG. 5 is a left view of the animal toy;

FIG. 6 is a top view of the animal toy; and,

FIG. 7 is a bottom view of the animal toy.

The broken lines shown in the drawings represent portions of the animal toy that form no part of the claimed design.
